(57) **CLAIM**

The ornamental design for a remote control, as shown and described

DESCRIPTION

FIG. 1 is a perspective view of a remote control showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dot-dash line represents the boundary between claimed and unclaimed areas. The areas shown in broken lines are environment only and form no part of the claimed design.

1 Claim, 6 Drawing Sheets
